[57] **CLAIM**

The ornamental design for a portable handset radio telephone, as shown and described.

DESCRIPTION

FIGS. 1 and 2 are respectively front and rear elevational views of a portable handset radio telephone showing my new design;

FIGS. 3 and 4 are respectively left and right side elevational views thereof;

FIGS. 5 and 6 are respectively top and bottom plan views thereof;

FIG. 7 is a cross sectional view taken on line VII—VII in FIG. 1 with the interior construction omitted;

FIG. 8 is a front, top and right side perspective view thereof; and

FIG. 9 is a front, top and right side perspective view of a second embodiment thereof, the difference of this embodiment, vis-a-vis the first, being showing of the handset telephone in operative condition with antenna raised, and with the display panel and sundry pushbuttons having conventional operative indicia.

The broken line showing of numerals in the display panel of FIG. 9 is for illustrative purposes only and forms no part of the claimed design.
